FIRE EXTINGUISHER

Harold O. Thompson, Doland, S. Dak.

Application January 23, 1940, Serial No. 315,253

1 Claim. (Cl. 299—96)

This invention relates to fire extinguishers, and more particularly to portable hand-operated extinguishers equipped for throwing an extinguishing fluid.

5 In accordance with the present invention there is provided an extinguisher embodying a receptacle for the extinguishing material, and which receptacle is of a material permitting perforation thereof, and is equipped for the connection thereto of a hand-operated pump for use in forcing the fluid in a stream from the receptacle.

The invention together with its objects and advantages will be best understood from a study of the following description taken in connection 15 with the accompanying drawing wherein—

Figure 1 is a side elevational view of the fire extinguisher.

Figure 2 is a detail sectional view taken substantially on the line 2—2 of Figure 1, and

20 Figure 3 is a detail sectional view taken substantially on the line 3—3 of Figure 2.

Referring more in detail to the drawing, the receptacle for the extinguishing fluid is indicated by the reference numeral 20 and is shown as 25 being in the form of a relatively shallow receptacle, provided with the flat end walls 22 and 23 and an externally threaded neck 21 is attached to the lower portion of the wall 22.

A hand pump 11 is used with the device and 30 includes the cylinder 12 having a piston 16 therein with the rod 15 having its inner end connected with the piston, the rod passing through a hole in the front end of the cylinder and the outer end of the rod has a handle 15' attached thereto. A cap 13 is attached to the rear end of the cylinder or barrel and includes a top part having a centrally arranged hole therein and an internally threaded cylindrical sleeve, the top part of the cap extending across the rear end of the 35 barrel or cylinder of the pump and being welded or otherwise attached to the cylinder or barrel as shown in Figure 2. This cap is to be threaded to the neck 21. A pin or piercing instrument 17 is connected with the piston and passes through the 40 hole in the top part of the cap as shown in

Figure 2. This pin or instrument 17 is of such a length that when the piston is moved toward the receptacle 20 said pin will pass through both walls 22 and 23 of the receptacles, to thereby provide, in an obvious manner, an air intake orifice 5 in the wall 22 and a fluid discharge opening or orifice in the wall 23 of the receptacle so that, in response to the operation of the pump 11, the extinguishing fluid will be discharged in a stream from the receptacle.

From the foregoing it will be seen that with my fire extinguisher the hand pump can be readily coupled to, or connected with the receptacle containing the extinguishing fluid, and when so coupled to the receptacle will serve as a handle 15 therefor while at the same time permitting facile operation of the pump for the initial perforating operation and consequent forceful discharge of the extinguishing fluid, in a stream, from the receptacle.

Many other advantages of a fire extinguisher embodying the features of this invention will readily present themselves to those skilled in the art.

Having thus described the invention what is 25 claimed as new is:

In a fire extinguisher, a hand pump including a barrel, a piston and a piston rod passing through one end of the barrel and having a handle on its outer end, a cap including a top part and an internally threaded cylindrical sleeve, the outer face of said top part being fastened to the other end of the barrel and said top part having a hole therein, a receptacle containing fire extinguishing fluid, a circular tubular neck connected to the lower part of one side of the receptacle and threaded exteriorly for receiving the threaded part of the cap and a long needle connected with the piston of the pump and passing through the hole in the top part of the cap, said needle being 40 of sufficient length to pass through both sides of the receptacle when the piston is pressed toward the receptacle.

HAROLD O. THOMPSON.
